APPARATUS FOR THE HEAT TREATMENT OF PEAT.

1,160,464.

Specification of Letters Patent. Patented Nov. 16, 1915.

Original application filed February 25, 1913, Serial No. 750,561. Divided and this application filed September 24, 1914. Serial No. 863,312.

To all whom it may concern:

Be it known that we, NILS TESTRUP, a subject of the King of Great Britain and Ireland, and residing at 3 Dean Farrar street, 5 London, S. W., England, and THOMAS RIGBY, a subject of the King of Great Britain and Ireland, and residing at 61 Loreburn street, Dumfries, Scotland, have invented certain new and useful Improvements in and Relating to Apparatus for the Heat Treatment of Peat, of which the following is a specification.

This invention relates to the treatment of peat by such process of heat treatment as 15 apparently by chemical decomposition of some component of the peat renders its water more freely removable, for example the wet carbonizing of the same.

In wet carbonizing peat in apparatus such 20 as has been proposed by Ekenberg (British Letters Patent No. 10834 of 1903) wherein rotating tubular elements are employed, the provision of the rotating elements is liable to be a source of substantial cost in operation, owing to wear and the need of replacement 25 of the parts, and moreover is a large factor in the initial cost of the apparatus. We have observed that if, instead of providing rotating scrapers and other devices 30 within the tubular and other elements, the peat pulp to be wet carbonized is forced through the apparatus at considerable velocity, it is possible by this means alone to prevent blocking and other difficulties which 35 the rotation of the elements was intended to avoid; and that it becomes unnecessary therefore to provide such rotating elements. We have discovered, however, that the high rate 40 of flow tends to result in incomplete wet carbonization due as it would appear from our experiments to the rate at which the carbonizing reaction proceeds having a limited velocity. The material requires therefore to be maintained for some appreciable period 45 at the requisite temperature before it is allowed to cool by transfer of its heat to a fresh quantity of the material. It must be borne in mind, however, that such time element in the reaction is, as our experiments 50 suggest, dependent upon the maximum temperature selected for wet carbonization, it becoming shorter with rising temperature and is also apparently dependent upon the degree of the decomposition or general na-

ture of the peat treated. The completion of 55 wet carbonization to the desired degree can be gaged by the readiness with which the macerated pulp delivered from the carbonizers parts with its water in a filter press or the like to give a coherent cake of relatively 60 low water content and unaccompanied by objectionable shining up of the cloths. In operating therefore with a high rate of flow of the peat pulp as above indicated, we make allowance for the above features. 65

The present invention consists in apparatus for the heat treatment, such as wet carbonization of peat, in which the peat is caused to flow at such a velocity through the apparatus that moving scraping or other devices become unnecessary, and in which the peat, after having been raised to the desired 70 wet carbonizing temperature or thereabout, is maintained at this temperature for a sufficient period to allow the carbonization to 75 complete itself to the desired extent.

This invention also consists in the improved apparatus for the heat treatment of peat as hereinafter described.

In the accompanying drawings Figure 1 80 shows diagrammatically one form of the apparatus according to this invention, while Fig. 2 shows to an enlarged scale a detail of said apparatus, and Fig. 3 an alternative form of apparatus.

The wet carbonizing element comprises 85 long concentric stationary tubes, say respectively of 3½ inches internal, 4 inches external and 5 inches internal diameter, and for instance between 700 and 1,000 feet in total 90 length, and which may be shown as divided into five sections or sets of tubes. Through the outer tubes *a* and *b*, of the first two sets of tubes a hot liquid, such as the effluent from the filter presses of the installation is 95 introduced at *c*, and passes through the tube *a*, bend *d* and tube *b*, in the direction indicated by the arrows, and thereafter passes to the outlet *e*, for example to any suitable waste such as the moss. The raw peat to be 100 wet carbonized is forced into the apparatus by a pump *z* through the inner tube *f*, and flowing in a direction opposite to that of the hot effluent or other liquid receives heat from the latter and is thereby regeneratively 105 heated. On leaving the inner tube *f* by a bend *g*, the peat passes through the second inner tube *h*, where it is further heated while

its temperature gradually approaches that of the effluent entering the surrounding jacket at *c*. The partially heated peat is now conducted by a bend *i* to the inner tube *j*, in which it is further regeneratively heated, but in this case by the peat which has been wet carbonized, and is flowing in the opposite direction in the outer tube *k*. As the raw peat flowing through the tube *j* is thus surrounded by hot wet carbonized peat having a temperature which increases as the heating locality is approached, radiation of heat from the hot peat is preferably avoided as by arranging that the colder material, after passing through the tube *j*, is conducted by way of a bend *m* into the outer tube *n* of the next tube set, the inner one *c* of which contains the hot wet carbonized peat and conveys the same by way of a bend *p* to the outer tube *k*. In this way the colder material passing in the outer tube *m* forms to some extent a lagging which diminishes loss of heat.

The raw material on leaving the tube *n* then passes into an inner tube *q*, and having passed to the end thereof its direction of flow is reversed, and it passes through the outer concentric tube *r*. In this tube set the additional heat necessary to raise the temperature of the raw material to that which has been selected for the maximum is supplied by means of a steam jacket *s*, to which steam is supplied at a pressure of about 190 lbs. per square inch, such steam being obtained, for example, from a high pressure exhaust of a high pressure steam engine supplying power for the installation, and after leaving the jacket and being otherwise utilized is returned to the steam generating plant as feed water. By thus arranging that the colder material entering this part of the carbonizer is confined to the inner tube *q*, the advantage is obtained that the jacket wall is in direct contact with the material which is to be heated to the highest temperature. The material having now been raised to the required temperature leaves the tube *r* and passes by way of a conduit *t* into a closed vessel *u*, which is provided with a rotating mixer *v* and intermediate baffles *w*. The rate of flow of the material is by this means materially reduced, so that it remains for instance about twenty minutes although this may be substantially greater or less as indicated above in the vessel *u*, before passing into the conduit *x*, by which it is conveyed to the inner tube *o* of the regenerative part of the wet carbonizing element.

It will be understood that where in carrying this invention into effect several carbonizing elements and peat retaining vessels of the type above described are employed, the hot liquid which effects the preliminary regenerative heating of the raw peat may

be supplied to that regenerative part of several carbonizing elements from the same conduit, such regenerative parts in some cases being grouped together apart from the rest of the carbonizing elements. A mixing vessel may be provided for each carbonizing element, or if preferred several such elements may deliver the hot peat into the same vessel, or according to another arrangement the mixing vessels may deliver the carbonized peat into the same conduit from which it is distributed to the carbonizing elements for the purpose of effecting regenerative heating of the incoming raw material. Those regenerative portions pertaining to several carbonizers and in which hot peat pulp supplies heat may likewise be grouped together and the externally heated portions grouped in one or more steam jackets.

A rate of flow which we have found satisfactory for running the apparatus with stationary tubes was with a particular sample of peat pulp finely macerated and containing about 94 per cent. water 25 cms. per second to as much as 100 cms. per second or higher. We find the heat transmission per unit surface from peat to peat, and from steam to peat increases rapidly with an increase of velocity, and when working with a velocity of flow of about $2\frac{1}{2}$ ft. per second, a steam jacket of about 100 ft. in length is suitable. The length of the tube element in which the regeneration goes on varies with the velocity and the amount of heat which has to be transmitted or regenerated, and the difference in the temperature between the heat transmission surfaces. We find, for instance, that the length of tube element required when working with a velocity of $2\frac{1}{2}$ ft. per second is about 950 ft. in the regenerative portion, and in addition to the length in the steam jacket, this being with a difference of temperature on the regenerative heating surface of about 40° C. It is obvious that the length of tube can be varied to suit the conditions governing this heat transmission and the amount of regeneration required.

It is to be observed that principal features of the invention above set out are dependent upon our observation that if the peat pulp to be wet carbonized is forced through the apparatus at a considerable velocity, it is possible by this means alone to prevent blocking and other difficulties which the rotation of the elements in former apparatus (see British Patent specifications Nos. 10834 of 1903, 6041 of 1910 and 17610 of 1911) was intended to avoid. We have further observed, however, that with such rate of flow there is a tendency for incomplete carbonization and that as it would appear from our experiments, the rate at which the carbonizing reaction proceeds has a definite ve-

lacity, the material requires therefore to be maintained for some appreciable period at or about the maximum temperature before it is allowed to cool by transfer of its heat to raw material entering the carbonizer.

5 The pressure which may be required in the case of an apparatus of the dimensions which have been instanced to give the pulp the desired velocity through the apparatus has been observed by us with one particular peat finely macerated and containing say 10 93.5% of water to amount to several hundreds of pounds per square inch—800 lbs. in one particular experiment.

15 Although the maintenance of the heated peat for the required time at the predetermined temperature has been described as effected in a vessel of a special character separate entirely from the concentric tubular system, it will be understood this is referred 20 to by way of example only and that the result may be obtained as indicated in Fig. 3 by causing the peat to flow through a section of tube u' of the requisite length in which it 25 is merely prevented from losing its heat by suitable lagging means w' .

It is important in order to secure efficient heat regeneration, rapid heat transmission and general economy in the working of the 30 apparatus to insure a substantial agitation within the peat pulp flowing through the apparatus, and while the rapid flow alone produces apparently the movement necessary to prevent lodgment on the walls our experiments suggest a tendency to channeling or 35 stratification in the pulp. For this reason among others we prefer to provide specific baffling devices such as a diaphragm of the type seen at y in Fig. 2, and provided with a 40 large central orifice in the path of the flow and at suitable distances apart, these acting to produce a churning or eddying in the material. In order to prevent likelihood of deposition in the angles formed by these devices it is desirable to provide as shown a 45 coned approach to the diaphragm. Again, if cross connections be provided at intervals which interchange the streams of peat from annulus to core and vice versa, each interval 50 change will secure an agitation of the material.

An important advantage arising from alternately passing the peat which flows from and into the carbonizer through annulus and 55 core of the tube sets described with reference to the drawing, is that it enables a construction to be obtained in which as with that illustrated the raw peat passes to the maximum extent through the inner tubes of the system 60 this leading to a reduction of pressure required for propulsion owing to the raw peat with the relatively high viscosity or shear on the tube walls passing through that part where the proportion of surface of wall to 65 cross sectional area is least.

The apparatus may be constructed with any desired number of concentric tubes and layers of peat flowing therein. Thus the regenerator portion may be formed of four concentric tubes in alternate ones of which 70 flow respectively peat to and peat from the carbonizer portion proper.

Having now described our invention, what we claim as new and desire to secure by Letters Patent is:—

1. Apparatus for the heat treatment of peat, comprising concentric tubular stationary elements, through which the peat is passed while being heated, means connecting the space within the inner tube of one 80 element to an annular space of another, and means connecting the annular space of the first mentioned element with the inner space of the second.

2. Apparatus for the heat treatment of 85 peat, comprising in combination, concentric tubular heating elements, means external thereto for forcing the peat therethrough, and baffling means disposed within said elements at suitable intervals along 90 the length thereof.

3. Apparatus for the heat treatment of peat, having stationary concentric tubular elements through which the peat is forced 95 while being heated to about the desired maximum temperature and having a vessel separate from the tubular elements wherein the material is maintained at or about the desired temperature for the necessary period.

4. Apparatus for the heat treatment of peat having a plurality of sets of concentric tubular elements and means for interchanging the flow of peat between an inner tube space and an outer annular space, and between the latter space and the former.

5. Apparatus for the heat treatment of peat comprising in combination concentric tubular heating elements, forcing means effecting rapid passage through the inner tube space of peat being preheated regeneratively by treated peat passing through the annular tube space, means for further heating the preheated peat, a receptacle 110 separate from said elements for maintaining the heated peat at about the desired maximum temperature, until treatment is completed to the required extent, and means returning the completely treated peat to the annular regenerative tube space of the heating elements.

6. Apparatus for the heat treatment of peat, comprising in combination, concentric tubular stationary elements, forcing means effecting rapid passage of the peat 125 through said elements, heating means extending along part of the length of the elements, lagging means extending along a further length, and regenerative means extending along the remaining portion of the 130

length of said elements to preheat untreated peat by means of treated peat.

7. Apparatus for the heat treatment of peat, comprising in combination, concentric tubular stationary elements, forcing means effecting rapid passage of the peat therethrough, regenerative means receiving warm effluent expressed from treated peat to heat untreated peat, further regenerative means receiving hot peat to heat further the untreated peat warmed by said effluent, means for heating the preheated peat to the maximum temperature, and means for retaining the peat at about this temperature until heat treatment is completed to the desired extent.

8. Apparatus for the wet carbonization of peat comprising in combination stationary tubular heating elements, forcing means to effect rapid passage of the peat through said elements, steam heated means to heat the peat to the requisite maximum temperature, a receptacle in which the peat is maintained at or about said temperature until wet carbonization has been effected to the desired extent, heat regenerating means receiving peat from said receptacle to heat raw peat and heat regenerating means re-

ceiving from wet carbonized peat hot effluent to be used in heating raw peat.

30

9. Apparatus for the wet carbonization of peat comprising in combination stationary tubular heating elements, forcing means causing rapid passage of the peat through said elements, steam heated means to heat the peat to the requisite maximum temperature, a receptacle in which the peat is maintained at or about said temperature until wet carbonization has been effected to the desired extent, heat regenerating means receiving peat from said receptacle to heat raw peat, heat regenerating means receiving from wet carbonized peat hot effluent for heating raw peat, and interconnecting means by which the peat to be treated can be passed through and around said heat regenerating means.
